UNITED STATES PATENT OFFICE.

WALTER W. HOOVER, OF LIBERAL, KANSAS.

HEADING-SHEARS.

1,055,910.

Specification of Letters Patent. Patented Mar. 11, 1913.

Application filed June 19, 1912. Serial No. 704,634.

To all whom it may concern:

Be it known that I, WALTER W. HOOVER, a citizen of the United States, residing at Liberal, in the county of Seward and State of Kansas, have invented new and useful Improvements in Heading-Shears, of which the following is a specification.

This invention is an improved heading shear which is especially adapted for heading broom corn, Kafir corn, maize, cane, and other similar crops, the object of the invention being to provide an improved shear of this kind which operates to automatically grasp and hold the boot or lower end of the 10 cut stalk of the head and prevent it from dropping when cut, the invention consisting in the construction, combination and arrangement of devices, hereinafter described and claimed.

20 In the accompanying drawings:—Figure 1 is partly a side elevation and partly a sectional view of a heading shear constructed in accordance with my invention, and showing the same open. Fig. 2 is a transverse 25 sectional view of the same on the plane indicated by the line *a*—*a* of Fig. 1. Fig. 3 is a similar view on the plane indicated by the line *B*—*B* of Fig. 1. Fig. 4 is a detail elevation of the reverse side of the shear.

30 My improved heading shears comprise a pair of cutting jaws 1—2 which are here shown as made of sheet steel and are respectively provided with integral handles 3—4. These handles are in effect semi-tubular in 35 shape, so that they are hollow or channeled on their opposing sides. Each handle is connected to its jaw by an offset 5, the said offsets of the respective jaws crossing and being pivotally mounted on a bolt 6.

40 In connection with the cutting jaw 2, I provide a clamping jaw 7 which corresponds substantially with the jaw 2 in shape and size and is spaced therefrom, the offset portion 8 of the clamping jaw 7 being also pivotally mounted on the bolt 6 and the handle portion 9 of the clamping jaw being fitted in the channel of the handle 4 of said jaw 2 and terminating in a U-shaped arm 10 which fits in the channel of the handle 4 45 and engages a stop 11 which is turned inwardly from the outer side of said handle. A spacing sleeve 12 is placed on the pivotal bolt 6 between the jaw 2 and the clamping jaw 7 and on one end of the said pivotal bolt is a washer 13 which bears on the offset 8 of the jaw 7 and a nut 14 which bears on

the said washer. A locking arm 15 has an opening through which the pivotal bolt extends. This locking arm is arranged on the outer side of the offset 5 of the jaw 1, has 60 outturned sides 16 which bear against opposite sides of the head of the bolt and the said locking arm has its outer end turned inwardly at right angles as at 17 and extended through an opening 18 in one side of the 65 handle 4 of the jaw 2. This locking arm by thus engaging the head of the bolt prevents the latter from turning and hence, obviates all tendency of the nut working loose on the bolt.

70 A spring 20 has a coiled central portion 21 arranged around the spacing sleeve, the arms of the said spring being arranged in the channels of the handles 3—4 of the cutting jaws 1—2, and the said spring acting 75 against the said handles to keep the cutting edges normally open. A hand guard 22 extends from the lower side of the arm 3 and is formed of a piece of wire of suitable gage, the inner end of which extends through an 80 opening in the lower side of the said arm, the outer end of the said wire being clamped between the sides of the said arm at the outer end of said arm.

75 In connection with the clamping jaw 7, I employ a clamping arm 23 which is made of spring wire. The clamping arm is substantially U-shaped and arranged with its sides on opposite sides of the clamping jaw 7 so that the serrated edge 24 of said clamping 80 jaw is adapted to pass between the sides of said clamping arm. The terminals of the clamping arm are formed with coils 25 which are arranged on a stud 26 that projects from opposite sides of the clamping 85 jaw 7, the terminal portions of the clamping arm being arranged in the bottom of the channel in the handle 3 of the cutting jaw 1 and bearing at their ends under one arm of the spring which serves to open the jaws. 100 When the cutting jaws are closed their respective cutting edges move past each other so as to cut a stalk of cane, Kafir corn, or the like between them and the closing movement of the cutting jaws causes the extension or terminal of the spring clamping arm, by bearing against the bottom of the channel of the handle 3 to turn the said clamping arm on its pivot and move it toward the serrated edge of the clamping jaw. Hence, at 110 the same time that the cutting jaws close the clamping arm also closes against the ser-

rated edge of the clamping jaw and the said clamping arm and clamping jaw coact to grasp opposite sides of the stalk, which is being cut, and, hence, the stalk is held when 5 cut and is prevented from dropping.

In using the heading shears, the same are grasped by the right hand, the fingers being passed through the guard. When cutting a head of cane, broom corn, Kafir corn, or 10 the like, the user of the shears grasps the head with his left hand and then cuts the stalk of the head, the clamping jaw and arm coacting to hold the stalk while being cut and preventing it from slipping.

15 While I have herein shown and described a preferred form of my invention, I would have it understood that changes may be made in the form, proportion and construction of the several parts without departing 20 from the spirit of my invention and within the scope of the appended claims.

I claim:

1. Heading shears of the class described comprising a pair of cutting jaws having crossed, pivotally connected handles, a clamping jaw spaced from and movable with one of the cutting jaws, and a clamping arm pivotally connected to the said clamping jaw, arranged opposite the edge thereof, to 25 move toward and from the same and provided with an extension connected to and operated by the handle of the other cutting edge, the said clamping jaw having a pivotal stud projecting from opposite sides 30 thereof, and the said clamping arm comprises

ing a doubled wire having sprung coils arranged on the said stud on opposite sides of said clamping jaw and having side members spaced from and arranged on opposite sides of the plane of the clamping jaw.

2. The herein described heading shears comprising a pair of cutting jaws having crossed handles, the said handles having channels on their inner sides, a clamping jaw arranged opposite one of the cutting jaws and having an arm secured in the channel of the handle thereof, a pivotal bolt connecting the cutting jaws and the clamping jaws, a spring comprising a coiled central portion arranged on said pivotal bolt and 45 end portions bearing against the bottoms of the channels of the handles, and a clamping arm comprising a doubled wire, the said clamping arm being arranged opposite the edge of the clamping jaw and having its side 50 members spaced from and arranged on opposite sides of the plane of said clamping jaw, said side members of the clamping arm having spring coils and terminals, said terminals extending into the channel of the 55 other handle, and a pivot stud projecting from opposite sides of the clamping jaw and engaging the said spring coils of the clamping arm.

In testimony whereof I affix my signature 60 in presence of two witnesses.

WALTER W. HOOVER.
